EYELETING MACHINE FOR MATTRESS BORDERS

Application filed June 29, 1928. Serial No. 289,158.

This invention relates to improvements in eyeleting machines for mattress borders.

In certain types of mattresses the border portions are formed with rows of spaced metallic eyelets which serve to join the border layers. Heretofore difficulty has been encountered in the insertion of these eyelets, especially where the borders are of such width that the eyelets must be disposed in spaced transverse rows.

It is one of the objects of the present invention to provide a machine which will feed the several materials required for a mattress border so that the same will be disposed in their proper relation and then at intervals join said layers by transverse rows of a plurality of eyelets.

A further object of the invention is to provide a machine of the class described arranged to automatically insert transverse rows of eyelets into mattress border layers and then to automatically space the material for the next eyeleting operation.

A further object of the invention is to provide a machine of the class described arranged to have fed thereinto from different sources three separate layers of material, the machine rapidly delivering the material correctly joined by means of rows of eyelets.

A further object of the invention is to provide an eyeleting machine for mattress borders which is of very simple construction, is rapid, efficient and automatic in operation, is strong and durable, and is well adapted for the purposes described.

With the above and other objects in view the invention consists of the improved eyeleting machine and its parts and combinations as set forth in the claims, and all equivalents thereof.

In the accompanying drawings in which the same reference characters indicate the same parts in all of the views:

Fig. 1 is a side view of the improved mattress border eyeleting machine with a portion of the supporting table being shown in section;

Fig. 2 is an enlarged side view of the main machine portion with parts shown in section;

Fig. 3 is a front view of the machine portion shown in Fig. 2;

Fig. 4 is a side view opposite to that shown in Fig. 2 of the main machine portion;

Fig. 5 is an enlarged detail view, partly in section, of an eyelet inserting or punch member;

Fig. 6 is an enlarged detail view of an eyelet inserting or punch member showing the position of the parts upon the formation of a head on an eyelet;

Fig. 7 is a plan view of the eyelet containers and the tracks extending therefrom;

Fig. 8 is an enlarged detail sectional view taken on line 8—8 of Fig. 9;

Fig. 9 is an enlarged detail sectional view indicated on line 9—9 of Fig. 7; and

Fig. 10 is an enlarged detail sectional view taken on line 10—10 of Fig. 7.

Referring now more particularly to the drawings it will appear that the numeral 12 indicates a supporting table having a flat base portion 13, at one end of which the improved eyeleting machine, indicated generally by the numeral 14, is mounted. Said machine is formed with a pair of upstanding, spaced frame members 15 formed at their upper ends with bearings 16 in which is journaled a transverse crank shaft 17, one end portion of said shaft having mounted thereon, by means later to be described, a large drive wheel 18. Pivotally secured to and depending from the crank portion 19 of said crank shaft is a crank arm 20 which is pivotally mounted at its lower end portion on a rod 21 which

is carried fast by a pair of spaced lugs 22 projecting outwardly from a vertically movable angled plate 23. The large drive wheel 18 is driven by a belt 24 which extends to a pulley mounted fast on a shaft 26 with a larger pulley 27, the larger pulley being connected through a belt 28 with an electric motor 29. Said motor and the pulleys 25 and 27 are mounted below the base portion 13 of the table, as shown in Fig. 1.

Mounted fast on the end portion of the crank shaft 17 is a pulley member 30 having an outwardly extending sleeve portion 31 on which the large drive wheel 18 is mounted, there being a clutch engagement of any

55

60

100

common form between said drive wheel and the sleeve, controlled by a plunger 32 yieldably mounted within a groove 33 of said pulley member. An operating lever 34 is 5 pivotally mounted on the frame portion 15 and connected thereto is a vertical rod 35 normally maintained in a raised position by a spring 36 coiled thereabout. If the lever 34 be held downwardly, the rod 35 will be disengaged at its upper end portion from the groove 33 and plunger 32 and there will be a clutching engagement between the members 30 and 18 whereby they will turn together when the power is on. If the lever 10 34 be released, the upper end portion of the rod 35 will engage the plunger 32 and the clutch engagement between the drive wheel and member 30 will be released whereby the drive wheel will idle on the sleeve portion 31 15 and the crank shaft 17 will not be turned.

A slotted crank member 37 is connected fast to the outer end portion of the sleeve portion 31 and a wrist pin 38 is adjustably connected to the crank member, whereby the stroke of a 20 connecting rod 39, connected at its upper end portion to the wrist pin, may be varied. The lower end portion of the connecting rod is pivotally connected to the outer end portion of an arm 40 mounted fast on the end portion 25 of a shaft 41 which is journaled in the bearing portion of a supporting arm 42, and the other end portion of said shaft has pinned thereto an arm 43 at right angles to the arm 40. A dog member 44, movable against a 30 spring 45, is carried by the outer end portion of the arm 43. A cam 46 is mounted loosely on the end portion of the shaft 41 and its shoulders 47, separated by ninety degree angles, are adapted to be engaged by the dog 44, whereby said cam member is intermittently moved a quarter of a revolution. Also mounted loosely on the shaft 41 and secured to the cam 46, so as to make quarter revolutions therewith, is a gear 48 which is 35 in mesh with a gear 49 mounted fast on the end portion of an upper roller shaft 50. Said shaft 50 is journaled in adjustable bearings 51 and has mounted fast thereon a feed roller 52. A lower guide roller 53 cooperates 40 with the feed roller, and said guide roller is mounted on a shaft 54 below the shaft 50 and parallel thereto.

Extending upwardly and forwardly from the frame portion of the machine is an angular supporting arm 55 on the enlarged outer end portion of which are mounted three eyelet casings or boxes 56, 57 and 58, each being provided with a cover 59 to permit the loading of eyelets. The supporting arm, below 45 each box, is provided with a bearing in which is journaled a brush shaft 60, each brush shaft extending into its box and having mounted on its inner end portion a brush 61 and having mounted on its outer end portion a pulley 62. A belt 63 is extended around all of said

50 pulleys to drive the brushes, and said belt also extends over sheaves 64 and around the pulley member 30 on the crank shaft 17.

Eyelet raceways 65, 66 and 67 mounted on a surface of the supporting arm 55, extend 55 from the boxes 56, 57 and 58, respectively, to the lower curved end portion of said arm. When the brushes 61 within the boxes are revolved eyelets 68 within the boxes are tossed around and are ultimately worked, in proper 60 positions, through openings 69 in the sides of the boxes, each box opening registering with the raceway adjacent its box. The raceways 65, 66 and 67 are constructed as shown in Figs. 7 and 10 and the eyelets are held therein 65 as shown in Fig. 10 and descend by gravity to the lower end portions of the raceways. The lower end portion of each raceway is provided with a pair of movable, spring connected fingers 70 which engage and releasably hold the adjacent eyelets under their headed end portions for the eyeleting operation.

The vertically movable plate member has secured transversely to its lower end portion 70 a block 71 having a dove-tailed recess 72 which receives the dove-tailed portions 73 of three eyeleting punch members 74. The punch members 74 are provided with clamping bolts 75 engaging the bar 71 and by the dove-tailed arrangement said members 74 75 may be adjusted laterally, when required.

A punch member is shown in detail in Figs. 5 and 6 and will be seen to comprise a cylindrical portion 74' having a bore 76 extending 80 upwardly from its lower end portion. A reduced stem portion 77 is secured within the lower portion of the bore by the set screw 75' and depends from the portion 74', said stem portion having a reduced bore 78. An elongated plunger 79 is movably mounted within the bore 78 and its head 80 extends within the bore 76 and mounted on said head, within 85 the latter bore, is a coiled spring 81.

Mounted fast on a frame portion 82, below the punch members 74 and spaced therefrom, are three die members 83. Each die member has a recess 84 in which is positioned an upwardly projecting cylinder 85, the position of the cylinder being adjustable by means of an adjusting bolt 86. The frame portion 82 carries a movably mounted material supporting plate 87 which is yieldingly movable against the tension of a spring 88, having a tensioning adjustment 89. Said plate 87 supports a fed mattress border 90 between the punch members and the die members and is formed with a plurality of recesses or cut-out portions 91 to permit passage of the punching plungers 79.

In the construction of mattress borders with the improved eyeleting machine, a pile of ticking 92 is arranged rearwardly of the supporting table 12, as shown, and said ticking is extended over rollers 93 mounted at 925

the upper end portions of elongated posts 94 projecting upwardly from the table portion 13. The ticking 92 is then drawn downwardly and enters a guide apron 95 extended rearwardly from the machine frame 15, and is disposed between the punch members and the die members and between the rollers 52 and 53, which causes it to be fed forwardly.

A pile of ticking 96 for the under layer 10 of the mattress border is positioned under the table 12, as shown in Fig. 1, and said material is extended upwardly through a slot 97 in the table base 13 to a guide apron 98, and then between the punch members and 15 dies, over the supporting plate 87, to the feed rollers 52 and 53.

A large roll of cotton felt 99 is mounted on a roller 100 carried by an intermediate portion of the forward post 94 and said felt 20 provides the intermediate layer or stuffing for the mattress border. Said felt extends to an apron 101 and then between the rollers 52 and 53, interposed between the upper and lower ticking layers 92 and 96.

25 When the mattress border material is arranged as described and the machine is set in operation, it being necessary for the operator to hold the lever 34 down, the feed rollers will be intermittently turned through 30 the connecting rod 39, arms 40 and 43, cam 46, and gears 48 and 49 to feed the material forward a desired distance. Then, while the rollers are stationary, the crank 19, through the arm 20, will lower the plate 23 carrying 35 the punch members 74. As the punch members move downwardly the plungers 79 thereof will pass through the eyelets held ready for insertion at the ends of the tracks 65, 66 and 67, by the fingers 70, and the plungers 40 will also pierce the mattress border material, ultimately engaging projecting portions 102 of the die members. A further downward movement of the punch members will cause the punch members to engage and force the 45 eyelets into the material, as in Fig. 5, the plungers being movable in the cylinder bores 72 against the expansive force of the springs 81. Also, the lower end portions of the eyelets will be forced against the die members 50 and be flanged or headed thereby, as in Fig. 6. After this operation the plate carrying the punch members is raised, releasing the punch plungers from the inserted eyelets, said eyelets being in a spaced transverse row 55 and securing together the border material layers and giving it a tufted appearance. As shown in Fig. 2, the downward movement of the plate 23 is against the tension of a coiled spring 103, and a smaller coiled spring 104, 60 between the upper end portion of the plate 23 and a lug 105, cushions the upward movement of said plate. It should also be observed that the angular raceway supporting arm 55 is provided with intermediate lugs 106 65 through which a rod 107 extends to pivotally

attach said arm to the frame portions 14 and 15. During punching operations said arm 55 pivots slightly in a clockwise direction, in Fig. 2, against the force of a spring 108 mounted on a horizontal rod 109, and when the punch members are raised, said spring returns the arm to normal position. 70

After the punch plate is raised to normal position, through the mechanism described, the material is fed forwardly a predetermined 75 distance and then another transverse row of eyelets is inserted, and so on.

From the foregoing description it will be seen that the improved machine provides for having fed thereinto from three different sources, three layers of mattress border material. The machine feeds the material, inserts transverse rows of eyelets to secure the material layers together, and then spaces the material for the next eyeleting operation. 80 There is delivered from the machine a length of substantially completed mattress border, which, because of the eyelets, is especially suited for ventilated mattresses and is attractive. Also, the machine is simple and efficient in operation and is well adapted for the purposes described. 90

What we claim as our invention is:

1. A mattress border eyeleting machine, comprising a frame, a driving member mounted thereon, a plurality of elongated material guides extending from the rear of the frame to the front of said frame and converging thereat, a feed roller, a cam member connected therewith, a dog engageable with said cam member, connections between the dog and the driving member for turning the feed roller intermittently, a plurality of spaced eyeleting members arranged transversely to the material guide and in alinement, a plurality of eyelet containers mounted above the eyeleting members, an inclined raceway extended between each container and each eyeleting member whereby eyelets are fed from the containers to the eyeleting members by gravity, brush means within each of the containers and connected with the driving member for automatically transferring individual eyelets to the raceway there adjacent, each eyeleting member comprising a fixed heading die, and a vertically movable piercing and eyelet inserting member, a common connection between said piercing and inserting members and the driving member, and means for operating said connection intermittently to raise and lower said piercing and inserting members between intermittent movements of the feed roller. 115

2. An eyeleting machine, comprising a frame having a work surface, a driving member, a plurality of elongated converging material guides extending to said work surface from outwardly thereof, a feed roller, connections between the feed roller and the driving member for turning the feed roller in- 120 125 130

termittently, a plurality of spaced eyeleting members arranged transversely of the material guides and in alinement, a plurality of eyelet containers mounted above the eyeleting members, means for automatically feeding individual eyelets to said eyeleting members, each eyeleting member comprising a fixed heading die and a vertically movable piercing and eyelet inserting member, a common connection between said piercing and inserting members and the driving member, and means for operating said connection intermittently to raise and lower said piercing and inserting members between intermittent movements of the feed roller.

In testimony whereof, we affix our signatures.

MAX MARSACK.
NATHAN MARSACK.
SAM MARSACK.
DAVID RAFFELSON.
